UNITED STATES PATENT OFFICE.

ALFRED HEALD, OF PHILADELPHIA, PENNSYLVANIA, ASSIGNOR TO McCAL-
LUM, CREASE & SLOAN, OF SAME PLACE.

DESIGN FOR CARPET.

Specification forming part of Design No. 6,653, dated May 20, 1873; application filed April 24, 1873.

To all whom it may concern:

Be it known that I, ALFRED HEALD, of Philadelphia, Pennsylvania, have invented a Design for Carpet - Pattern, of which the following is a specification:

The nature of my design is fully shown in the accompanying photographic illustration. It consists of a series of adjoining wreaths, A, composed of flowers, leaves, and stems, arranged in a manner too clearly shown by the drawing to need description, there being in the center of each wreath a figure, B, of

the character represented, and from which radiate bars a.

Irrespective of the colors employed, I claim—

The design for a carpet-pattern, substantially as described, and as shown in the accompanying drawing.

In testimony whereof I have signed my name to this specification in the presence of two subscribing witnesses.

Witnesses: ALFRED HEALD.
